UNITED STATES PATENT OFFICE

94,068

DESIGN FOR AN ELECTRIC HEATER FOR HAIR WAVING

Harry Bonat, New York, N. Y., assignor to Samuel Bonat and Harry Bonat, doing business as Samuel Bonat & Bro., New York, N. Y.

Application October 23, 1934, Serial No. 53,726

Term of patent 7 years

To all whom it may concern:

Be it known that I, Harry Bonat, a citizen of the United States, residing at New York city, county of New York, State of New York, have invented a new, original, and ornamental Design for Electric Heater for Hair Waving, of which the following is a specification, reference being had to the accompanying drawing, forming part thereof.

I claim:
The ornamental design for an electric heater for hair waving as shown.

HARRY BONAT.
